UNITED STATES PATENT OFFICE.

CLYDE KYRLE RABER, OF NEWCASTLE, INDIANA.

CAN SPOUT.

Application filed December 14, 1922. Serial No. 608,863.

To all whom it may concern:

Be it known that I CLYDE KYRLE RABER, a citizen of the United States, residing at Newcastle, in the county of Henry, State of Indiana, have invented a new and useful Can Spout; and I do hereby declare the following to be a full, clear, and exact description of the invention, such as will enable others skilled in the art to which it appertains to make and use the same.

The invention relates to spouts for cans, and has for its object to provide a device of this character which may be easily and quickly attached to a can and easily removed from the can after the contents has been poured therefrom.

A further object is to provide a can spout comprising a hollow cylindrical member, one end of which is provided with an angularly shaped cutaway portion, thereby forming the cutting edge for forming a hole in the can when the cylindrical body is forced therein. Also to provide the cylindrical body with a disc, which disc is provided with oppositely disposed can piercing members having notches for the reception of the edges of the holes formed by the can piercing members upon a partial rotation of the device.

80 A further object is to provide a resilient washer for forming an air tight joint between the flange and the can when the spout is attached thereto.

With the above and other objects in view the invention resides in the combination and arrangement of parts as hereinafter set forth, shown in the drawing, described and claimed, it being understood that changes in the precise embodiment of the invention 40 may be made within the scope of what is claimed without departing from the spirit of the invention.

In the drawing:—

Figure 1 is a side elevation of a can, part thereof being shown in section and showing the spout attached thereto.

Figure 2 is a perspective view of the detachable spout showing the same before being reversed for forcing into the can.

50 Figure 3 is a top plan view of the can, showing the holes formed therein by the device.

Figure 4 is a top plan view of a can showing the device attached thereto.

55 Figure 5 is a vertical transverse sectional view through the detachable spout.

Referring to the drawing, the numeral 1 designates a conventional form of can, for instance a condensed milk can, or a syrup can, from which it is present practice to pour the contents by punching a hole therein. However where a hole is used for pouring the contents from a can, the contents thereof accumulates on the can, especially where syrups or condensed milk is being poured, and consequently draw flies and is unsanitary. To obviate this difficulty the detachable spout 2 is provided, which spout is adapted to be attached to the can and after the contents thereof have been consumed, the spout is removed and used on another can. It is to be understood that the spout may be used in connection with any kind of a can, and no matter what the contents thereof may be.

The spout 2 comprises a cylindrical member 3, which member is provided with an annular flange 4, soldered or otherwise secured thereto. The annular flange 4 is disposed intermediate the ends of the spout 2, and has secured thereto by soldering at 5, a handle member 6 adapted to be grasped by the operator for imparting a partial rotation to the spout after the end 7 thereof has been forced through the can cover 8, for forming the round hole 9. The round hole 9 is formed by the cutting edges 10 of the cylindrical member 3. The end of the cylindrical member 3 is cutaway at an angle so as to form the cutting edges 10, and at the same time forms an entrance passage 11 to the spout 3, the upper end 12 of which terminates adjacent the top 8 of the can, thereby allowing all of the contents of the can to be poured from the can. The annular flange 4 at opposite sides of the cylindrical member 3 is provided with sharpened lugs 13, which lugs when the spout is forced into the cover 8, pierce the cover 8 and form apertures 14 at opposite sides of the aperture 9. The sharpened lugs 13 adjacent their inner ends are provided with recesses 15, which recesses upon a partial rotation of the spout as a whole receive the ends 16 of the apertures 14 and securely hold the spout in position on the can. However to prevent leakage around the spout, a washer 17 is provided, which washer is compressed when the spout is forced downwardly and partially rotated, consequently an airtight connection is formed between the spout and can cover.

From the above it will be seen that a can spout is provided, which is simple in construction, positive in its operation and one which may be easily and quickly attached or detached from a can. If so desired a spout cap 17 may be utilized, and frictionally held in place.

The invention having been set forth what is claimed as new and useful is:—

- 10 1. The combination with the wall of a can, of a removable spout therefor, said spout comprising a hollow cylindrical member having its ends open, one end of the hollow cylindrical member being cutaway at 15 at an angle, thereby forming inclined cutting edges adapted to form a hole in the can wall when forced therethrough, an annular flange carried by the cylindrical member, piercing lugs carried by the flange at 20 opposite sides of the cylindrical member and provided with notches for the reception of the end walls of apertures formed by the members upon a partial rotation of the cylindrical member.
- 25 2. A detachable spout for a can, said spout comprising a cylindrical member having a

chamber extending entirely therethrough, one end of the cylindrical member being cutaway at an angle, thereby forming an oval shaped entrance and cutting edges 30 adapted to be forced into a can cover for forming a round opening therein, an annular flange carried by the cylindrical member, an outwardly extending handle member carried by the flange, V-shaped lugs 35 carried by the flange at opposite sides of the cylindrical member and provided with notches at opposite sides thereof, a washer carried by the lug side of the flange and adapted to be compressed after the cutting end of the cylindrical member has been forced through the can and partially rotated for locking the can in the notches of the lugs.

In testimony whereof I have signed my 45 name to this specification in the presence of two subscribing witnesses.

C. KYRLE RABER.
